UNITED STATES PATENT OFFICE

KELLIS H. BURTON AND HERMAN KRAMER, OF TULSA, OKLAHOMA, ASSIGNORS, BY MESNE ASSIGNMENTS, TO THE PHILIP CAREY MANUFACTURING COMPANY, A CORPORATION OF OHIO

PIPE WRAPPING MACHINE

Application filed May 10, 1930. Serial No. 451,227.

Our invention relates to wrapping machines and more particularly to apparatus of that character for wrapping pipes and like cylindrical objects.

5 Before laying steel conduits in the ground, a coat of asphalt or like preservative is commonly applied to the outer surface of the pipe to prevent deterioration thereof. Due to the inherent drawing qualities of the soil, 10 the preservative tends to become disengaged from the pipe and adheres to the soil. In order to retain the coating of asphalt in intimate contact with the conduit, a layer of paper, preferably in the form of strips, is 15 wound around the pipe. This operation has heretofore, been ordinarily accomplished in factories by rotating the pipe to wind paper thereon from a spool supported in stationary brackets.

20 The principal object of this invention is to provide an apparatus for winding paper around a stationary pipe in the field, from a roll supported on a frame rotated around the pipe.

25 A further object of our invention is to provide means for readily adjusting the amount of lap applied to the successive turns of covering material when wound spirally around a conduit.

30 Other objects of the invention are to provide means for preventing adhesion of the traction rollers to the preservative coating, including means for applying additional covering to the portion of the conduit requiring a heavy covering.

In accomplishing these and other objects of our invention we have provided improved details of structure the preferred form of which is illustrated in the accompanying drawings, wherein:

Fig. 1 is a detail perspective view of a pipe wrapping machine embodying our invention, mounted in operable position on a pipe-line.

45 Fig. 2 is a central vertical section of the device mounted on a conduit, in pipe wrapping relation.

Fig. 3 is a plan view of the wrapping machine, parts being shown in section to better illustrate their structure.

50 Fig. 4 is a front elevational view of the

device mounted on a conduit illustrated in cross-section.

Referring more in detail to the drawings:

1 designates a pipeline preferably supported above the ground in a position to be 55 coated with a preservative and wrapped with paper prior to being permanently laid in the ground.

Mounted on the pipe or conduit is a pipe- 60 wrapping machine 2 including spaced frame members 3 and 4, having horizontal portions 5 and inclined legs 6, the members 3 and 4 being preferably formed of angle bars comprising flanges 7 and 8 directed outwardly 65 and downwardly respectively.

Cross bars 9 and 10, fixed to the flanges 7 of the horizontal portions 5 by bolts 11, space the frame members and are provided with aligning bearing portions 12 and 13 respectively for a purpose presently described. 70

Extended downwardly at right angles to the frame members and from the forward ends thereof are legs 14 and 15, also preferably constructed of angle bars, including inner flanges 16 fixed to the frame members 75 by rivets 17, and outwardly directed flanges 18 in alignment with the flanges 7 of the frame members.

Rotatably supported between the lower ends of the downwardly extending legs 14 and 15, in bearings 20 fixed in the legs, is a threaded shaft or axle 21, carrying spaced rollers 22, each roller comprising inner and outer flanges 23 and 24, having complementary facing sleeve portions 25 and 26 threaded on the shaft, a resilient tire 27 provided with an outwardly tapering rim 28, being received between the flanges. Collars 29 threaded on the shaft adjacent each flange serve to lock the rollers in adjusted relation to the shaft, the distance for spacing the rollers depending on the diameter of the conduit being wrapped. 85

In like manner a threaded axle 30, mounted between the inclined rear legs 6, in bearings 31, carries spaced rollers 32, identical in construction to the rollers 22 previously described. 95

The frame and rollers above described provide a truck adapted to be longitudinally 100

moved on the pipeline and to rotatably support the wrapping mechanism 33, including a yoke frame 34, provided with an arch 35 extending upwardly between the longitudinal portions 5 and the frame member, and fixed to the cross bar 9 and to the inner flange 8 by bolts 36.

Attached to the opposite faces of the yoke frame are duplicate yoke plates 37, having neck portions 38 formed complementary to the arch 35 of the frame, and downwardly extending arcuate arms 39 and 40, spaced at their lower ends by blocks 41 and 42 secured thereto by bolts 43. Lower portions 44 of the blocks are extended below the ends of the arms 39 and 40 to mount spaced bars 45 and 46, normally secured thereto by bolts 47, but detachable from the arm to permit mounting of the yoke members over a conduit.

With the construction above described, a substantially circular opening 48 is formed in the yoke member for receiving a rotatable carrier ring 49, including a relatively thin rim portion 50, adapted to be mounted in grooved rollers 51 interposed between the yoke plates and between the spaced bars on bolts 52 in an equally spaced, annular series surrounding the axis of the rotating ring.

A removable section 53, having slots 54 for receiving tongues 55 on the carrier ring, is provided for admitting the conduit into the carrier ring when mounting the wrapping machine on the conduit, bolts 56 extended through aligning openings in the tongues of the ring and grooved ends of the section serving to maintain the ring parts in assembled condition.

A ring gear 57 spaced from the front face of the carrier ring by collars 58 and secured thereto by rivets 59 extending through aligning openings in the collars, gear, and carrier, is provided with a removable section 60 fixed to section 53 of the carrier so that said section may be removed jointly therewith when mounting the machine on a conduit.

Mesning with the ring gear 57 is an idler gear 61 rotatably mounted on a bolt 62, extended through a concentric opening 63 in the gear, through openings 64 in the neck portions of the yoke plates, and through a spacing collar 65 mounted between the plates. An enlarged portion 66 of the bolt forms a shoulder 67 for seating against the front yoke plate, and a nut 68 is threaded on the bolt to securely mount the idler gear in alignment with the ring gear.

Journalled in the bearing portions 12 and 13 of the plates 9 and 10 is a shaft 69, and keyed to the shaft between said bearing portions is a driving pinion 70 meshing with the idler gear 61. Secured to the forward end of the shaft 69, by a key 71, is a bevel gear 72 adapted to mesh with a bevel pinion 73 fixed to a transverse shaft 74, journalled in bearings 75 and 76 secured to the outer ends of the

frame members 3 and 4 by bolts 77. The shaft 74 may be rotated from either end by a crank 78 removably mounted on squared end portions 79 of the shaft.

From the foregoing it will be apparent that by rotating the crank, the ring gear is rotated at reduced speed around the conduit and this reduced rotary movement is utilized for winding a strip of covering material around the conduit from a spooling mechanism 80, supported on the ring gear by a bracket 81, having a shank 82 extended through an opening 83 in the gear and threaded on its outer end for receiving a nut 84.

Provided on the rear end of the bracket is a ball portion 85 for seating in a complementary socket 86 of a spool head 87, on the inner end of a tubular shaft 88, rotatably supporting a roll of covering material or paper 89.

The supporting bracket is further provided with an arcuate slot 90 for receiving a curved arm 91, pivotally attached by a pin 92 between ears 93 integral with the head of the spool.

A series of openings 94 in the curved arm are adapted for selectively receiving a pin 95 extended through aligning openings in the bracket member and through one of the openings in the curved arm, so that the spool of wrapping material may be adjusted in angular relation to the ring gear to effect a greater or less amount of lap when winding material spirally around the conduit.

Means for applying tension to the roll of wrapping material to prevent unrestrained rotation thereof, includes a bar 96, having a head 97 on one end slidably movable on a shaft 98 integral with the head of the spool, a spring 99 being attached to the spool and to the head portion for normally urging the bar into engagement with the paper. The opposite end of the bar terminates in an inwardly depending flange 100 and attached thereto is a cord or the like 101 running over a pulley 102, mounted in the end of the tubular pulley shaft, the inner end of the cord being attached to a spring 103 anchored in said tubular portion.

In order to simultaneously move the wrapping machine longitudinally on the conduit while rotating the carrier ring, a primary driving sprocket 104 is fixed on the shaft 74 in aligning relation with a sprocket 105, keyed to a shaft 106, journalled in bearings 107, secured to the facing flange 18 of the angle members 14 and 15 by bolts 108, a chain belt 109 running over the sprockets 104 and 105. Lateral movement of the shafts 74 and 106 is prevented by collars 110 fixed to said shafts adjacent the inner faces of the bearings.

A smaller sprocket 111, further secured to the shaft 106 adjacent the sprocket 105, is connected by a chain belt 112 with a final

driven sprocket 113 fixed on the axle 21 mounted in the downwardly extending legs 14 and 15 of the frame.

5 Due to the reduction in speed of the final driven sprocket in relation to that of the primary driving sprocket, the wrapping machine is moved longitudinally on the conduit at a very low rate of speed.

10 In order to prevent adhesion of the traction rollers to the preservative on the conduit, especially during warm weather, we have provided means, now to be described, for laying a track of paper or the like on the conduit ahead of the traction rollers, the track further serving as additional protection for the preservative when throwing dirt on the conduit to fill the ditch.

15 Secured to the lower ends of the facing flanges 18 of the legs 14 and 15, by rivets or the like 114, are bracket members 115 having forwardly directed lateral ears 116 for pivotally receiving therebetween the arms 117 and 118 mounted on aligning bolts 119.

20 Rotatable on a shaft 120 extended through aligning openings on the outer ends of the arms 117 and 118, is a spool 121 adapted to receive a roll of track-laying material 122.

25 A pipe wrapping machine constructed as described is assembled on a conduit by removing the bars 45 and 46 and the connected sections of the driving gear and carrier ring. With the traction and trailer rollers supporting the machine on the conduit, the removable sections are again secured to the carrier ring and the bars 45 and 46 are again attached to the yoke, the outer ends of the wrapping or track-laying rollers are secured to the conduit and the crank is mounted on either end of the shaft 74 to suit the convenience of the operator.

30 Upon rotation of the crank, the machine is slowly drawn along the pipe by the traction rollers running over the track laid from the roll 122. Simultaneously the carrier ring is 45 rotated through the train of driving, idler and driven sprockets, carrying therewith the roll of wrapping material.

35 If it is found, upon winding the conduit, that an insufficient amount of lap is produced in the spiral windings, the pin 95 is inserted through the next upper opening 94 in the curved arm to effect a greater inclination of the wrapping roll in relation to the carrier ring. To decrease the amount of lap, it will be obvious that a reverse movement of the roll is necessary.

40 If the coating of preservative is sufficiently firm to prevent adherence of the traction rollers thereto, the track-laying apparatus may be readily detached from the machine by removing the bolts 119.

45 What we claim and desire to secure by Letters Patent is:

1. In a machine for wrapping conduit, a frame including traction rollers movable on

the conduit, a wrapping roll carrier on the frame, means for supporting a roll of track-laying material on the frame, and means for simultaneously moving the carrier longitudinally and rotatably on the conduit to 70 wind the wrapping material spirally around the conduit and to lay a track of material on the conduit for the traction rollers.

2. In a machine for wrapping conduit, a frame including traction rollers, a carrier rotatably mounted on the frame and surrounding the conduit, a spool pivotally mounted on the carrier, means for supporting a roll of track-laying material on the frame, means for rotating the carrier in the frame to wind material from the spool around the conduit, and means for moving the frame longitudinally for laying a track of material on the conduit 75 for the traction rollers.

3. In a machine for wrapping conduit, a frame including traction rollers, a carrier rotatably mounted on the frame and surrounding the conduit, a spool pivotally mounted on the carrier, means for adjusting the spool in angular relation with the carrier, means for supporting a roll of track-laying material on the frame, means for simultaneously rotating the carrier in the frame to wind material from the spool around the conduit, and for moving the frame longitudinally for laying a 80 track of material on the conduit for the traction rollers.

4. In a machine for wrapping conduit, a frame, traction wheels arranged in adjustable pairs for supporting said frame on a conduit, a carrier rotatably mounted in said frame and surrounding said conduit, a spool of track laying material carried by said frame in advance of said traction wheels and adapted to lay a track thereunder longitudinally of said conduit, a spool of wrapping material rotatably mounted on said carrier, the axis of said spool being inclined to the axis of the conduit, whereby the material is wound spirally about said conduit, means for varying the inclination of said spool, thereby varying the inclination of said spiral wrapping about said conduit, and means for moving said frame longitudinally of and rotating said carrier and spool about said conduit simultaneously.

5. In a machine for wrapping conduit, a frame, traction means supporting the frame and arranged to travel longitudinally on the conduit, means on the frame for supporting a roll of covering material and arranged for depositing the covering material in a longitudinal strip on the conduit ahead of said traction means whereby said traction means operates on said covering material, and means supported on the frame carrying a second roll of covering material for lapping the longitudinal strip of covering material.

6. In a machine for wrapping conduit, a frame, traction means supporting the frame 130

and arranged to travel on the conduit, means on the frame for supporting a roll of covering material and arranged for depositing the covering material on the conduit ahead of said traction means whereby said traction means operates on said covering material, and means supported on the frame carrying a second roll of covering material for lapping said strip of covering material.

10 7. In a machine for wrapping conduit, a frame, traction means supporting the frame and arranged to travel on the conduit, and means on the frame for supporting a roll of covering material and arranged for depositing the covering material in a longitudinal strip on the conduit ahead of said traction means, whereby said traction means operates on said covering material.

15 8. In a machine for wrapping conduit, a frame, traction means supporting the frame, a carrier rotatably mounted on the frame for supporting a roll of covering material, means on the frame for supporting a roll of track laying material, and means for operating the traction means to move the frame longitudinally of the conduit for depositing the track material on the conduit for said traction means and for simultaneously rotating said carrier for wrapping the covering material around the conduit.

20 9. In a machine for wrapping conduit, a frame, traction means supporting the frame and movable along the conduit, a carrier on the frame for supporting a roll of wrapping material, means for simultaneously actuating said traction means and rotating said carrier for winding the wrapping material spirally around the conduit, and means associated with the frame for laying a track for the traction means progressively with the winding of said wrapping material.

25 In testimony whereof we affix our signatures.
